UNITED STATES PATENT OFFICE.

EDWARD F. KENNEY, OF WESTMONT BOROUGH, PENNSYLVANIA.

BRAKE-BEAM

1,116,439.

Specification of Letters Patent. Patented Nov. 10, 1914.

Application filed July 11, 1912. Serial No. 850,290.

To all whom it may concern:

Be it known that I, EDWARD F. KENNEY, a citizen of the United States, residing in the borough of Westmont, whose post-office address is Johnstown, in the county of Cambria and State of Pennsylvania, have invented certain new and useful Improvements in Brake-Beams; and I do hereby declare the following to be a full, clear, and exact description of the invention, such as will enable others skilled in the art to which it appertains to make and use the same.

In trussed brake beams formed by splitting a rolled shape and using one portion for the compression member and the other for the tension member there is an element of weakness due to the insufficient means and material for transmitting the stress from the compression member to the tension member and vice versa. There is always a tendency to extend the cut, made in shearing, by tearing the two members apart, and this is resisted only by the strength of the thin portion of the rolled section which is necessarily made light to facilitate shearing. This thin section of metal is also inefficient in its resistance to the stresses due to the ragged edges or small cracks produced by the shear cut.

30 The results of even a small degree of failure, at the point referred to, is a considerable increase in the deflection of the beam under load, or its failure at the junction of the two members.

35 By upsetting the metal in the rolled section and forming it preferably hot so that the end sections thereof are thickened and thereby reinforced, the connections between the compression and the tension members are made strong, rigid, and unyielding so that danger of failure as stated above, is removed.

In connection with the above, the end portions of the beam can be so formed as to 45 make a more suitable support for the brake shoe, thereby obviating the necessity of the additional member ordinarily used, and reducing the number of parts and the lost motion attendant thereon, under condition 50 of use, which reduction of lost motion is a desideratum.

In the accompanying drawings, I have shown my invention applied to a brake beam formed from a rolled cruciform section, 55 which has been chosen merely for illustration, for, as will be readily understood, from

the description hereinafter set forth, my invention may be applied to any brake beam formed by splitting a rolled shape and using one portion for the compression member and 60 the other portion for the tension member.

Referring now to the accompanying drawings in which like characters of reference designate like parts:—Figure 1 is a plan view of a brake beam showing in dotted lines 65 the brake heads, shoes and a strut member. Fig. 2 is a plan view of a modified form of brake beam. Fig. 3 is a section on the line III—III of Fig. 1. Fig. 4 is an end view of Fig. 1 showing the brake head and shoe attached to the brake beam. Fig. 5 is a section through the center of Fig. 2 and corresponds to the section III—III of Fig. 1.

In the operation of forming my improved brake beam a rolled shape is split and spread 75 apart to form a truss with a compression member 1 and a tension member 2. The portions of the truss intermediate and adjoining the junction 3 and the ends of the beam are upset by any desirable method that will 80 increase the cross sectional area of the end portions 5 between the junction 3 and the end 4; thereby greatly reinforcing the said parts and forming a very rigid joint between the compression and the tension members. 85

The enlarged portions 5 of the brake beam may be so formed as to be received by and conform to the general shape of the socket 6 of the brake head 7 as shown in Fig. 4. Rivet or bolt holes 8 formed in the enlarged 90 portions 5 and the brake head 7 receive rivets or bolts 9 which securely fasten the brake head to the brake beam.

As in the usual construction, a strut member, shown in dotted lines in Fig. 1 of the 95 drawings, separates the tension and compression members of the brake beam. This strut member may be of any convenient construction.

The dotted line 10 in Fig. 4 shows the 100 original section of the rolled shape and the full line 11 is the general outline of the enlarged portion 5. It will be apparent from the comparison shown in Fig. 3 and in Fig. 4 that the union or junction 3 of the compression and tension members will be greatly reinforced, by the increased amount of metal 105 as indicated at 12 and elsewhere.

The modified form of brake beam, as shown in Fig. 2, is of substantially the same 110 construction as the brake beam shown in Fig. 1, the only change being that the en-

larged portions 5 are bent to the positions 13 so that said enlarged portions are substantially parallel with the tension members rather than with the compression members, thereby allowing the transmission of stress to take place with less strain in the materials of construction. Any desired brake head may be attached to the modified form of brake beam, in a manner similar to 10 that shown in Fig. 4.

Although I have shown and described my improvements in considerable detail, I do not wish to be limited to the exact construction shown and described, but may use such 15 substitutions, modifications or equivalents thereof, as are embraced within the scope of my invention or as pointed out in the claims.

Having thus described my invention what I claim and desire to secure by Letters Patent is:—

1. A trussed beam comprising compression and tension members integral and upset at their ends.
2. A trussed beam comprising compression and tension members integral and upset at their ends, and thereby enlarged in cross section.
3. A trussed beam comprising compression and tension members integral and upset 30 at their ends, and thereby enlarged in cross section, said enlarged portions being substantially parallel to the tension members.
4. A trussed brake beam comprising com-

pression and tension members integral and upset at their ends, thereby enlarged in cross 35 section, brake heads and shoes supported on the said enlarged portions.

5. A trussed brake beam comprising compression and tension members integral and upset at their ends, thereby enlarged in cross 40 section, brake heads and shoes supported on the said enlarged portions, and a strut member intermediate of and bearing against the compression and tension members.

6. A trussed beam comprising compression and tension members integral and upset at their ends, thereby enlarged in cross 45 section, said enlarged portions being parallel to the said tension members, and brake heads and shoes supported on the enlarged 50 portions of the beam.

7. A trussed beam comprising compression and tension members integral and upset at their ends, thereby enlarged in cross 55 section, said enlarged portions being parallel to the said tension members, brake heads and shoes supported on the enlarged portions of the beam, a strut member intermediate of and bearing against the compression and tension members.

In testimony whereof I hereto affix my signature in the presence of two witnesses.

EDWARD F. KENNEY.
